UNITED STATES PATENT OFFICE.

ROBERT D. PATERSON, OF PEORIA, ILLINOIS.

SAFETY LOCK FOR VAULT DOORS.

Application filed April 14, 1922. Serial No. 552,570.

To all whom it may concern:

Be it known that I, ROBERT D. PATERSON, a citizen of the United States of America, and resident of Peoria, Peoria County, Illinois, have invented a new and useful Safety Lock for Vault Doors, of which the following is a specification.

An object of this invention is to provide an improved safety lock for vault and safe doors to prevent chance or involuntary occupants of the vault from being locked therein by the main locking mechanism and also to prevent reopening of the door by an unauthorized or uninstructed person after he has attempted to close and lock the same.

A further object of this invention is to provide improved means normally operating to prevent complete closing of the door, thereby preventing operation of the main locking mechanism.

A further object of this invention is to provide improved means to prevent reopening of a vault door after attempted closing thereof by an unauthorized or uninstructed person such as a robber.

A further object of this invention is to provide means to render inoperative the last-mentioned means, for normal closing and locking of the door.

A further object of this invention is to provide improved mechanical means to operate the supplementary locking mechanism by and through contact with the door frame.

A further object of this invention is to provide an emergency or supplementary locking means comprising a hook on the door adapted to engage with the door frame or an element rigidly carried thereby, to prevent reopening of the door after attempted closing by an unauthorized or uninstructed person, and means for automatically moving said hook to operative position by and through closing movement of the door.

With these and other objects in view, my invention consists in the construction, arrangement and combination of elements hereinafter set forth, pointed out in my claims and illustrated by the accompanying drawing, in which—

Figure 1 is a plan view, partly in section, showing a portion of a vault or safe door equipped with my improved emergency safety lock. Figure 2 is an inner elevation of the same elements, partly in section. Figure 3 is an end elevation of the operating elements, on an enlarged scale, partly in

section on the line 3—3 of Figure 1. Figure 4 is a detail section on the line 4—4 of Figure 3. Figure 5 is a view similar to Figure 1, showing the parts in operative position. Figure 6 is a cross-section on the line 6—6 of Figure 5. Figure 7 shows a modified form.

Robbers attempting to hold up and rob a bank often force the cashier, clerks or other guardians into the vault and lock the door so as to be undisturbed in their operations. It is to overcome and prevent this that I have designed this safety or emergency locking mechanism for the vault door, which operates automatically by and through the attempted closing of the door to prevent complete closing and therefore renders impossible the locking of the door by the usual bolt work or locking mechanism. My device operates further to prevent the robber or other unauthorized person from reopening the door when he discovers that his attempts to close and lock it are vain, thus safeguarding the occupants of the vault from the robber and permitting them to employ any means which may be provided, such as a telephone within the vault, to communicate with the exterior to summon aid. I also provide means which prevents this emergency locking mechanism from functioning at times, as when it is desired to close and lock the door for the night, the emergency means, however, being brought automatically into position for functioning when the door is again opened, and rendered operable through closing of the door unless the releasing means is again set manually.

In the drawings the numeral 10 designates the body or plate of a vault door having an internal flange 11 spaced from its margins, through which flange the common bolts or locking bars (not shown) are adapted for reciprocation by common means to engagement with the door frame 12, the door 10 being hung in said frame by means of hinges 13. A block 14 is mounted on the uppermost flange 11 of the door near the hinged margin thereof, and is secured to said flange as by cap screws 15. An emergency locking hook 16 is mounted on said flange 11 at a distance from one end of the block 14 and is pivoted near one end to said flange by means of a cap screw 17. Ordinarily the locking hook 16 is held, by means to be described, in a position resting on and extending longitudinally of the flange 11, as shown by solid lines

in Figure 1; and when such holding means is released said hook is adapted to be moved to a position at right angles to such normal position, as indicated by dotted lines in 5 Figure 1, for engagement with a member such as 18 rigidly carried by the door frame or projecting downwardly from the roof of the vault. When the hook 16 is so engaged, the door of course is prevented from being 10 reopened. In the present instance I have shown a spring 19 coiled on the screw 17 in a recess in the hook and engaging said hook at a point spaced from its fulcrum, it being the function of said spring to tend to 15 move and hold said hook in operative position, that is projecting from the flange at an angle as indicated by dotted lines in Figure 1. The hook 16 is held in inoperative position, against the pressure of the spring 19, 20 by a keeper member 20 of angular form in plan view. The stem of the angular keeper 20 is disposed on the flange 11 between the block 14 and door plate 10 and the extension or head of said keeper projects between the 25 end of said block and the butt end of the hook 16 and in contact with said hook; and when said keeper is in horizontal position on the flange 11, such contact with the hook holds the latter member in inoperative position. A rock shaft 21 is journaled in 30 and transversely of the block 14 and the keeper 20 is fixed at the end of its stem to said rock shaft by means of a set screw 22. A rectangular recess 23 is formed in one 35 end of the block 14, at that side farthest from the door plate 10, and an operating member 24, substantially square in cross-section, is mounted in said recess and on the rock shaft 21, which projects within said 40 recess. Means is provided for detachably connecting the operating member 24 to the rock shaft, as shown in detail in Figure 4, for oscillation of said rock shaft with said operating member. The rock shaft 21 is 45 formed with a radial notch or seat 25 where it is engaged by the operating member, which latter member is formed with a longitudinally extending bore or recess 26. Mounted in the recess 26 of the operating 50 member is a latching pin 27, the inner end of which is adapted to enter the notch or seat 25 of the rock shaft and form an operative connection between said members. The outer end of the recess 26 of the operating 55 member is closed by means of a plate 28 having a slot 29 through which the pin 27 projects. The pin is yieldingly held to latching position by a spring 30 coiled thereon within the recess 26 and engaging at one 60 end the inner face of the plate 28 and at its opposite end a shoulder 31 on said pin. At times the pin 27 may be withdrawn longitudinally to release it from the seat 25, by 65 manually grasping a head 32 formed on its outer end; and may be held in such released position by means of a shoulder 33 on said pin adapted to engage the plate 28 at the lower end of the slot 29 when the pin is withdrawn and slightly depressed manually. When so depressed and engaged, the head 32 70 of the pin projects slightly beyond the lower margin of the plate and operating member 24, as indicated by dotted lines in Figure 4. In practical use the parts are assembled and arranged as shown and described. 75 When the door is opened by the attendant to commence the day's business, provision is made, as hereinafter described, whereby it follows that the pin 27 is engaged in the seat or notch 25 so that the operating 80 member is operatively connected to the rock shaft. In this position, the keeper 20 being in its normal position, flat on the flange 11, the operating member is inclined at an upward angle from said flange, as said operating member and keeper are not in the same plane when the operative connection is effective. When so arranged, the free end of the operating member 24 projects above the horizontal plane of the lower margin 85 of the top of the door frame 12, such horizontal plane being indicated by the dotted line 12 in Figure 2. The operating member 24 is beveled on top on that side farthest from the door 10, that is to say on the 90 side which first approaches the door frame 12 in closing of the door, such beveling being indicated by the numeral 34. Furthermore, when the parts are in the position described, the hook 16 is in inoperative 95 position longitudinally of and resting on the flange 11, being held in such position by contact of its butt end with the head of the keeper 20, against the tension of the spring 19. In the event it is attempted 100 to close the door while the parts are so positioned, as by a robber or other unauthorized person designing to lock the attendants or guardians in the vault, the closing movement of the door causes the beveled margin 105 of the operating member 24 to engage the lower margin of the top member of the door frame 12. The operating member 24 normally is held in its upwardly inclined 110 position by means of a spring 35 secured 115 at one end to the block 14, coiled on the rock shaft and engaging said operating member at a point spaced from said rock shaft. Its engagement with the door frame causes the operating member 24 to be depressed against the action of the spring 35, toward a horizontal position, thus rocking the shaft 21 and lifting the free end 120 of the keeper 20. As the keeper 20 is considerably longer than the operating member 24, the lifting movement is amplified at the free end of the keeper, so that a slight depression of the operating member by contact with the door frame causes a material 125 raising of the free end of said keeper, suffi- 130

cient to carry such free end above the plane of the hook 16 and release its holding engagement with said hook. This permits the hook 16 to move through an arc of about 5 ninety degrees, under the influence of the spring 19, to a position substantially perpendicular to the door plate 10. Such lifting of the keeper 20 also serves to carry its free end materially above the plane of 10 the lower margin of the top member of the door frame 12, whereby, lying between the door plate 10 and said frame, it prevents complete closing of the door. Unless the door is completely closed in its frame, it 15 cannot, of course, be locked by means of the ordinary locking mechanism, for the locking bolts cannot be shot to their seats, or being shot fail to enter their seats in the frame. When the robber discovers 20 that his attempts to close and lock the door are vain, he is very apt to attempt to reopen the door to threaten or coerce the occupants of the vault. By this time, however, the released and spring-pressed hook 25 16 has traveled into position for engagement with the rigid member 18, the hook being beveled at its end to facilitate such engagement, which effectively prevents re-opening of the door until said hook is 30 released. This may be accomplished manually from within the vault when the robbers have left or assistance has arrived. When the emergency has passed, the parts may be placed in their normal positions shown 35 by solid lines, in which position they are inoperative yet ready to function upon attempted closing of the door.

When the door is to be closed for the night, or at any time when it is not desired 40 to use the locking hook 16, the operating member 24 is disconnected from the rock shaft by withdrawal of the pin 27, and engagement of the shoulder 33 thereof with the plate 28 at the lower end of slot 29. 45 Then the operating member is oscillated manually to depressed position, the end of the pin 27 passing beyond the seat 25, or is depressed automatically by closing of the door and consequent engagement of the 50 beveled margin of said operating member by the door frame as previously described. As the operating member is now detached from the rock shaft, such movement has no effect on the keeper 20 or hook 16. As 55 the operating member 24 is moved to horizontal position by the engagement just described, the projecting end of the head 32 of the latching pin engages the upper surface of the flange 11 and sufficient pressure is exerted to release the shoulder 33 of the 60 pin from contact with the plate 28 and permit the spring 30 to move the pin inwardly toward and into engagement with the rock shaft 21, at a point below the seat 65 25. Thereafter, when the door is opened,

the operating member is raised by the spring 35 and the pin automatically reseats in the notch or seat 25, so that the mechanism is automatically placed in position for operation by operative connection of the operating member with the rock shaft. When the door is completely closed the operating member normally is held in depressed position by parts of the door frame; or if the door frame is not so constructed as to function in this manner, a special member may be provided for the purpose.

My mechanism may also be employed in association with, while not directly connected to, a pressure bar system such as is 80 sometimes used to facilitate closing of a vault door. When so used my improved devices function in the manner hereinbefore described to prevent complete closing of the door and consequently prevent engagement 85 of the pressure bars in their seats.

In Figure 7 I have illustrated a construction in which the spring 19 to throw the hook into operative position is dispensed with. Instead the hook 16' is provided with a mechanical connection to the keeper member 20, by means of a cable 36, or other flexible member, secured at one end by means of a screw 37 to the hook at a point beyond its fulcrum, and secured at its opposite end to the member 20 by means of a screw 38. When the keeper 20 has moved out of 90 holding engagement with the hook, draft is applied through the cable 36 to cause 95 the hook to move into operative engagement 100 with a member such as 18.

I do not desire to be understood as limiting myself to the precise construction and arrangement of parts herein shown and described, as various modifications, within the scope of the appended claims, may be employed without departing from the spirit of my invention.

I claim as my invention—

1. The combination with a door frame and door hinged therein, said door being formed with a flange on its inner face, of a member pivoted on said flange and adapted to be moved beyond the margin of said door and across the plane of the adjacent margin of the door frame, an operating member secured to and extending at an angle with said member, and a yielding pressure device normally holding said operating member away from said flange and across the plane of said door frame, said operating member adapted to be engaged and oscillated by said door frame in closing movement of the door to throw said first mentioned member across the plane of the door frame and prevent complete closing of the door.
2. The combination with a door frame and a door hinged therein, said door being formed with a flange on its inner face, of a member pivoted on said flange and adapted

- to be moved beyond the margin of the door and across the plane of the adjacent margin of the door frame, an operating member secured to and extending at an angle with
- 6 said member and beveled on one margin, and a spring acting to hold said operating member away from said flange and across the plane of said door frame, said operating member adapted to be engaged on its bevelled margin by said door frame and oscillated in closing movement of said door to throw the first mentioned member across the plane of the door frame and prevent complete closing of the door.
- 10 15 3. The combination with a door frame and a door hinged therein, said door being formed with a flange on its inner face, of a member pivoted on said flange and adapted to be moved beyond the margin of the door
- 20 25 and across the plane of the adjacent margin of the door frame, an operating member detachably connected to said member, and a spring acting to hold said operating member away from said flange and across the plane of said door frame, said operating member adapted to be engaged and oscillated by said door frame in closing movement of the door to throw the first mentioned member across the plane of the door frame and between
- 30 35 said door frame and the door to prevent complete closing of the door.
4. The combination with a door frame and a door hinged therein, said door being formed with a flange on its inner face, of a member pivoted on said flange and adapted to be moved beyond the margin of the door and across the plane of the adjacent margin of the door frame, an operating member connected with said member, a spring acting
- 40 45 to hold said operating member away from said flange and across the plane of the margin of the door frame, said operating member adapted to be engaged and oscillated by said door frame in closing movement of the door to throw the first mentioned member between the door and door frame and prevent complete closing of the door, and a locking hook pivoted on said flange, said door frame being formed with an element
- 50 55 adapted to be engaged by said hook to prevent opening of the door, said hook being moved to operative position when said first mentioned member is oscillated.
- 60 65 5. The combination with a door frame and a door hinged therein, said door being formed with a flange on its inner face, of a member pivoted on said flange and adapted to be moved across the plane of the adjacent margin of said door frame, an operating member connected with said member, a spring acting to hold said operating member away from said flange and across the plane of the margin of the door frame, said operating member adapted to engage and be oscillated by said door frame in closing

movement of the door whereby the first mentioned member is moved to position between the door and door frame, and a spring-pressed locking hook pivoted on said flange, said door frame being provided with a rigid element to be engaged by said hook to prevent reopening of the door, said first mentioned member operating to hold said hook in inoperative position until oscillated by said operating member.

6. The combination with a door frame and a door hinged therein, said door being formed with a flange on its inner face, of a rock shaft suitably journaled and carried by said flange, a member secured to said rock shaft and adapted to be moved beyond the margin of the door frame, an operating member secured to said rock shaft and lying in a different plane from said member, a spring acting to hold said operating member away from said flange and across the plane of the margin of the door frame, said operating member adapted to engage and be oscillated against the action of said spring by said door frame when the door is moved to closed position, thereby rocking said shaft and moving the first mentioned member to a position between the door and door frame, a hook pivoted on said flange, said door frame being provided with a member to be engaged by said hook to prevent reopening of the door, and means set in motion by oscillation of said first mentioned member to move said hook to operative position.

7. The combination with a door frame and a door hinged therein, said door being formed with an internal flange, of a rock shaft suitably journaled and carried by said flange, a member secured to said rock shaft and adapted to be moved across the plane of the adjacent margin of the door frame, an operating member pivoted on said rock shaft, a spring-pressed latching pin adapted to detachably connect said operating member to said rock shaft, a spring acting to hold said operating member away from said flange and across the plane of the margin of the door frame, said operating member adapted to engage and be oscillated by said door frame in closing movement of the door whereby said first mentioned member is thrown between the door and door frame, thereby preventing complete closing of the door.

8. The combination with a door frame and a door hinged therein, of a rock shaft suitably journaled and carried by said door, a member secured to said rock shaft and adapted to be moved across the plane of the adjacent margin of the door frame, an operating member loosely engaging said rock shaft, a spring-pressed latching pin adapted to detachably connect said operating member to said rock shaft, said operating member normally extending across the plane of the

margin of the door frame and adapted to engage and be oscillated by said door frame in closing movement of the door, whereby the first mentioned member is thrown between the door and door frame, and means to hold said latching pin in inoperative position.

9. The combination with a door frame and a door hinged therein, of a rock shaft suitably journaled and carried by said door, a member secured to said rock shaft and adapted to be moved across the plane of the adjacent margin of the door frame, an operating member loosely engaging said rock shaft, a spring-pressed latching pin adapted to detachably connect said operating member to said rock shaft, said operating member normally extending across the plane of the margin of the door frame and adapted to engage and be oscillated by said frame in closing movement of the door, whereby the first mentioned member is thrown between the

door and frame, means to hold said latching pin in inoperative position, and means to release said latching pin from holding position in the oscillation of said operating member.

10. In a device of the class described, a rock shaft formed with a seat, a member loosely engaging said rock shaft and formed with a longitudinal recess, a latching pin mounted in said recess and adapted to enter said seat, a spring tending to hold said pin to its seat, a plate closing the outer end of said recess, said plate being formed with a slot through which said pin projects, said pin being formed with a shoulder adapted to engage said plate at the edge of said slot to hold said pin out of its seat.

Signed at Des Moines, in the county of Polk and State of Iowa, this 12th day of April, 1922.

ROBERT D. PATERSON.
